UNITED STATES PATENT OFFICE.

DAVID F. HAYNES, OF BALTIMORE, MARYLAND.

DESIGN FOR AN EWER OR JUG.

SPECIFICATION forming part of Design No. 20,450, dated January 6, 1891.

Application filed November 28, 1890. Serial No. 372,980. Term of patent 3½ years.

To all whom it may concern:

Be it known that I, DAVID F. HAYNES, a citizen of the United States, residing at Baltimore, Maryland, have invented and produced a new and original Design for an Ewer or Jug, of which the following is a specification, reference being had to the accompanying drawings, forming a part hereof.

Referring to the said drawings, Figure 1 is an exterior side elevation of the ewer, and Fig. 2 a top view of the same.

I describe the ewer or jug as follows: Its base A is cylindrical. The body B is a frustum of a spheroid, which is fluted at the upper end, and the upper edge of the body, as seen from the side, is waved. The spaces between the flutes are decorated with a common foliated design in relief. The edge of the

body between the flutes is curved outward, and thereby gives to the top of the ewer a 20 waved outline, as seen in Fig. 2. The handle is decorated with a foliated design in relief and attached to the body at its upper end between the flutes.

I claim as my invention. 25
The design for an ewer herein described and shown, the same comprising the body having the general form of a frustum of a spheroid, with its upper end fluted and curved outward and decorated with a foliated design in relief, 30 the base, and the handle, substantially as described.

DAVID F. HAYNES.
